(57) **CLAIM**

The ornamental design for a pet hair dryer as shown and described.

DESCRIPTION

FIG. 1 is a front perspective view of a pet hair dryer;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a front perspective view of the pet hair dryer with a hose, a handle, and a nozzle attached thereto.

The broken lines in the drawings depict portions of the pet hair dryer that form no part of the claimed design.
